UNITED STATES PATENT OFFICE.

CLARENCE M. FAITHFULL, OF LIBERTY, MISSOURI.

INTEREST-BEARING INSTRUMENT OF OBLIGATION.

1,141,452.

Specification of Letters Patent.

Patented June 1, 1915.

Application filed May 4, 1911, Serial No. 625,001. Renewed April 27, 1915. Serial No. 24,345.

To all whom it may concern:

Be it known that I, CLARENCE M. FAITHFULL, a citizen of the United States of America, residing at Liberty, in the county of 5 Clay and State of Missouri, have invented certain new and useful Improvements in Interest-Bearing Instruments of Obligations, of which the following is a specification.

This invention relates to general negotiable interest-bearing instruments of obligations and more particularly to what is termed a negotiable certificate of deposit and has for its object to provide a certificate of deposit in a manner as hereinafter set forth 10 which may be issued for any one or a number of amounts and which is provided with means in a manner as hereinafter set forth which will automatically calculate or add the interest for a given length of time, or 15 from one given interest date or period to another given interest date or period. Although the invention is designed to be used as a certificate of deposit, yet it is to be understood that it can be used for any purposes 20 25 wherein it is found applicable.

The principal object of the invention is to provide an instrument of the foregoing type with means in a manner as hereinafter set forth adapted when occasion so requires to 30 indicate the interest for a given length of time, the interest indication or indicia appearing in proximity to the amount of the principal so it can be quickly added to the principal, or the indication being such as to 35 include the interest and principal.

With the foregoing and other objects in view, the invention consists of the novel construction and arrangement of interest bearing instruments as hereinafter more 40 specifically described and illustrated in the accompanying drawings, wherein is shown embodiments of the invention, but it is to be understood that changes, variations and modifications can be resorted to which come 45 within the scope of the claims hereunto appended.

In the drawings, wherein like reference characters denote corresponding parts throughout the several views: Figure 1 is a front view of an interest-bearing instrument in accordance with this invention. Fig. 2 is a front view of the instrument folded showing the interest indication or indicia exposed through the instrument and in proximity to the principal. Fig. 3 is a rear view of the instrument broken away. Fig. 4 is a front 50 55 view of a modified form of interest-bearing

instrument in accordance with this invention. Fig. 5 is a front view of the form shown in Fig. 4 folded and with the indication or indicia indicating the amount of principal and interest exposed through the instrument and in proximity to the amount of the principal. Fig. 6 is a rear view broken away of the form shown in Fig. 4. 60 Fig. 7 is a front view of another modified form of interest-bearing instrument in accordance with this invention. Fig. 8 is a front view of the form shown in Fig. 7 folded and with the indication or indicia indicating the amount of principal and interest exposed through the instrument and in proximity to the amount of the principal. Fig. 9 is a rear view broken away of the form shown in Fig. 7. Fig. 10 is a front view of another modified form of interest-bearing instrument in accordance with this invention, the front section being shifted with respect to the rear section. Fig. 11 is a front view of the rear section broken away, of the 70 75 form shown in Fig. 10. Fig. 12 is a front view of the form shown in Fig. 10 folded and with the indication or indicia indicating the amount of principal exposed through the instrument in proximity to the amount of 80 85 the principal, and, Fig. 13 is a rear view broken away of the front section of the instrument illustrating the means for indicating the amount of interest for each coupon.

Referring to Figs. 1, 2, and 3 of the drawings, 90 95 100 105 110 115 120 125 130 135 140 145 150 155 160 165 170 175 180 185 190 195 200 205 210 215 220 225 230 235 240 245 250 255 260 265 270 275 amount for which the certificate can be issued and to one side of the spaces 17 is arranged a column of spaces 19, these spaces 19 being in alinement with the spaces 17 and 5 each of which is adapted to be punched as at 20 to designate the amount for which the certificate has been issued. Above the indications 18 an inscription 21 is provided to designate that the amount for which the 10 certificate is issued is to be punched in the associating space 19. Above the inscription 21 a suitably-designated opening 22 is arranged through which is adapted to be exposed the end of the interest period when the interest is to be computed. The opening 15 20 associates with the opening 22 in this particular, that when the number of months or end of the interest period is exposed through the opening 22, the amount of interest 25 is exposed through the opening 20 at the side of the amount for which the certificate is issued. The front of the body-portion 10 at one end is provided with an inscription as at 23 indicating how the certificate 30 is to be manipulated so that the amount of accrued interest will appear through the opening 20 at the side of the amount for which the certificate is issued. The back of the body-portion 10 is provided with interest scales 34 which associate with the amounts, \$1.00, \$5.00, \$10.00, and \$25.00, but it is obvious that the scale can be changed to associate with any amount for which the certificate is issued. The back of the body-portion 10 is also provided with indicia as 35 at 25 for indicating the interest periods, these latter being complementary to the indications of each interest scale 24.

The form as shown in Figs. 4, 5 and 6 of 40 the drawings is for use where there are regular interest periods and is provided with means for indicating full value of a certificate at the end of a given interest period. Referring to said figures, the body-portion 45 of the certificate is indicated as at 26 and which has its front provided with the name of the bank issuing the certificate as at 27, an inscription as at 28 certifying to the amount deposited, and also including the 50 rate of interest, the inscription 28 is provided with a blank space 29 for the name of the depositor and a blank space 30 for the reception of the amount for which the certificate is issued. The front of the body-portion 26 is also formed with a suitably-55 designated space 31 for the name of the cashier of the bank and an appropriately-designated space 32 for the reception of the signature of the depositor. Below the inscription 28 is an inscription 33 for indicating the manner in which the certificate is to 60 be manipulated so as to indicate the full value thereof at a given interest period. To one side of the inscription 28 a column of spaces 34 is provided, each of which con-

tains an amount for which the certificate may be issued as at 35. At the side of the column of spaces 34 a column of spaces 36 is provided, each of which is adapted to be punched to provide an opening 37 at the 70 side of and to designate the amount for which the certificate is issued. Above the columns of spaces 34 and 36 is an inscription 37^a to designate for what purpose the said columns of spaces are utilized. Above the 75 inscription 37 is an appropriately-designated column of dates 38, with either one of which is adapted to associate a notch 39 to indicate the beginning of the interest period. The opening 37 in one of the spaces of 80 the column of spaces 36 is appropriately-designated as at 40 to indicate for what purpose the opening 37 is also intended. The notch 39 is appropriately-designated as at 41 to indicate for what purpose said notch 85 is used. The opening 37 and notch 39 associate with each other in this particular,—that when the certificate is folded back to ascertain the value of the certificate at a given interest period, the date of the last interest 90 period is exposed through the notch 39 and the full value of the certificate is exposed through the opening 37. The back of the body-portion 26 is provided with scales 42 for setting forth the full value of the certificate at the end of a given interest period, by way of example, the certificate is shown as to be issued for the amount of \$1.00, \$10.00, or \$25.00 and a scale 42 associates with each of said amounts, but it is to be 95 understood that the certificate can be issued for any amount desired and the scales 42 will be changed accordingly. The back of the body-portion 26 is also provided as at 100 43 with means to constitute a series of regular interest periods which are exposed through the notch 39 when the certificate is folded and which are complementary to the indications of each interest scale 42.

Referring to Figs. 7, 8, and 9 of the drawings, the form of certificate set forth is the same as that shown in Figs. 4, 5, and 6 with the exception that one end edge is utilized when the certificate is folded to be positioned at the last interest period and at the 110 amount to indicate the interest and principal. The body-portion is indicated by the reference character 44 and the said edge by the reference character 45. The date of the instrument is checked as at 46 and the 115 amount of the principal is also checked as at 47. The rear face of the body-portion is provided with a series of interest bearing dates as at 48. In Fig. 8, the instrument is shown folded to the interest bearing period, 120 October, 1911. The face value of the instrument is \$10.00. It will appear upon the back of the instrument when folded in the position shown in Fig. 8 that the edge 45 at 125 the interest bearing date October, 1911, that 130

the amount of interest and principal will be \$10.30.

With the form shown in Figs. 10 to 13 both inclusive, the body-portion is constructed of a front section 50 and a rear section 51. The front section has its front face provided with means to indicate the name of the issuing bank, and an inscription certifying that the depositor has deposited a certain sum of 10 money which is payable upon the surrender of the certificate properly indorsed with all unmatured coupons attached, the interest being at the rate set up by the issuing bank. The inscription has arranged therein blank 15 spaces for the name of the depositor and the amount of the instrument. By way of example, the rate of interest is set forth at 4% computed quarterly from the date of issue of the certificate, but it is to be understood 20 that any desired rate can be employed. The inscription is referred to generally by the reference character 52. Below the inscription 25 52 an appropriately designated space 53 is provided for the signature of the cashier and below the inscription is an appropriately designated space 54 for the signature of the depositor. The front of the section 50 to one side of the inscription 52 is provided with a column of spaces 55, in 30 each of which is arranged as at 56 an amount for which the certificate can be issued and to one side of the spaces 55 is arranged a column of spaces 57, these spaces 57 being in alinement with the spaces 55 and each of 35 which is adapted to be punched as at 58 to designate the amount for which the certificate has been issued. Above the indications 56 is an inscription 59, to designate that the amount for which the certificate is issued is to be punched in the associating space 57. The front of the section 50 is provided with an inscription 60 indicating where the value 40 of each interest coupon is shown. The rear face of the section 50 is provided with two 45 rows of spaces, one indicated by the reference character 61 and the other by the reference character 62. The spaces 61 associate with the spaces 57 and in each of the spaces 62 is arranged an interest amount as at 63. The spaces 62 associate with the spaces 55 and the interest amounts 63 associate with the amounts 56 for which the certificates are issued. Below the spaces 62 is arranged an 55 inscription 64 which is explanatory with respect to the interest amount 63. When one of the spaces 57 is punched, one of the spaces 61 is punched. When one of the spaces 57 is punched, it indicates the amount for which the certificate is issued and at the same time 60 the punching simultaneously indicates the value of the interest coupon. The section 50 is furthermore provided with an opening 65 through which is adapted to be exposed the number of months passed since the date of 65 issue of the certificate. Below the inscrip-

tion 52 and on the front of the section 50 is an inscription 66 indicating how the certificate is to be manipulated so that one can find the value of an interest coupon. The inner face of the section 51 is provided with four 70 interest coupons, indicated at 67, 68, 69, 70, each provided with interest bearing indicia as at 71, so that the value of the coupon can be indicated. The interest bearing indicia is similar to that as disclosed at 61, 62, and 63 75 upon the inner face of the section 50. The value of each coupon is indicated by a suitable check mark as at 72 and which corresponds to the amount indicated at 62 upon the inner face of the section 50. Each of 80 the coupons is provided with an interest period as at 73.

By reference to Fig. 12, it will be observed that the section 50 has been folded so that the opening 65 will have exposed therethrough the interest period 6 and the value 85 of the coupon which is 50¢ will appear through the opening 58.

Any one cashing the coupons will check the value of the coupons in the space provided above the amounts on the coupons as 90 at 72.

In Figs. 2, 5, and 8, the body-portion of the certificate is shown folded, in Fig. 2, the accrued interest being exposed through the 95 opening 20, in Fig. 5 the full value of the certificate exposed through the opening 37, and in Fig. 8, the full value of the certificate being set forth in proximity to the edge 45.

It will be assumed that one desires to ascertain the amount of interest due at the expiration of fifteen (15) months upon a certificate issued for \$25.00. The body-portion of the certificate would be folded upon 105 itself so that the indication 15 would be exposed through the opening 22 and simultaneously with the exposing of the indication 15 through said opening 22, \$1.25 would appear through the opening 20,—this would 110 indicate to the owner of the certificate that the exact amount was \$1.25, making the full value of the certificate \$26.25.

It will be assumed that the form of certificate shown in Fig. 4 is issued for \$1.00 115 for a given interest period and that the owner of the certificate desires to ascertain what the value of the certificate is, say by way of example, on Oct. 1, 1911, the certificate bearing interest from Jan. 1, 1911. 120 The certificate is folded back until the indication Oct. 1911 is exposed through the notch 39 and simultaneously with the exposing of the indication Oct. 1911 through the notch 39, there would be exposed through 125 the notch 37 \$1.03, indicating to the owner that the full value of the certificate is \$1.03. If the form of certificate shown in Fig. 7 is used, and say, it was issued on Jan. 1, 1911, for \$10.00 and on Oct. 1, 1911, the owner 130

4
of the certificate desiring to ascertain the full value thereof, will fold the certificate back until the date Oct. 1911 is exposed at the edge 45 and simultaneously with the exposure of each date, the full value of the certificate will appear in proximity to the edge 45, for example, \$10.30 as shown in Fig. 8.

In actual use, the certificate could be made 10 in many different variations to constitute the needs of the individual banker, such as to the rate of interest, whether compounded or not, conditions under which interest commences, continues and is payable.

15 By providing the column of spaces for the reception of varying amounts for which the certificate can be issued, the banker can have a number of different denominations on one form thereby overcoming the necessity of having each certificate for an independent amount and as the certificate is provided with an interest scale for each denomination or amount for which the certificate can be issued, it is obvious that the 20 interest can be found with a minimum of mental effort.

It is obvious that the interest amount indications provide a fixed indication of interest amount due or interest amount and principal 30 due at any one of a plurality of successive interest periods. At maturity of any one of the interest periods, the certificate may be taken up and redeemed by the payment of the principal and the interest then due. As 35 the instrument is negotiable, the interest amount indications will set forth the interest value of the certificate at any intermediate period and enables an equitable transfer of the certificates from one party 40 to another without redemption.

What I claim is:

1. An interest bearing certificate of obligation comprising a body-portion having a certificate portion on its obverse face and 45 interest amount indicating portion on its reverse face, the certificate portion including indicia for selectively indicating amounts, said interest indicating portion having indicia representing periods of elapsed time and also indicia representing interest amounts, the interest amount indicia including separate interest amount values for each 50 amount value of the certificate, said certificate portion having means for permitting visual inspection of both a selected time period and the correlated interest amount for the selected certificate amount when the interest amount portion is folded upon the reverse face of the certificate portion.

60 2. An interest bearing certificate of obligation comprising a body-portion having a certificate portion on its obverse face and interest amount indicating portion on its re-

verse face, the certificate portion including indicia for selectively indicating amounts, 65 said interest indicating portion having indicia representing periods of elapsed time and also indicia representing interest amounts, the interest amount indicia including separate interest amount values for each 70 amount value of the certificate, said certificate portion having means for permitting visual inspection of both a selected time period and the correlated interest amount for the selected certificate amount when the interest amount portion is folded upon the reverse face of the certificate portion.

3. An interest bearing certificate of obligation comprising a body-portion having a certificate portion on its obverse face and 80 interest amount indicating portion on its reverse face, the certificate portion including indicia for selectively indicating amounts, said interest indicating portion having indicia representing periods of elapsed time 85 and also indicia representing interest amounts, the interest amount indicia including separate interest amount values for each amount value of the certificate, said certificate portion having means for permitting 90 visual inspection of both a selected time period and the correlated interest amount for the selected certificate amount when the interest amount portion is folded upon the reverse face of the certificate portion, said means including an opening through the certificate adjacent the selected certificate amount.

4. An interest bearing certificate of obligation comprising a body-portion having a 100 certificate portion on its obverse face and an interest amount indicating portion on its reverse face, the certificate portion including indicia for selectively indicating amounts, 105 said interest indicating portion having indicia representing periods of elapsed time and also indicia representing interest amounts, the interest amount indicia including separate interest amount values for each amount value of the certificate, said certificate portion having windows therein adjacent the certificate indicia amounts, the interest amount portion of the certificate adapted to be folded upon the reverse face of the certificate portion whereby when the 110 two portions are superposed visual inspection of the selected time period and correlated interest amount data may be had through the windows.

In testimony whereof I affix my signature 115 in presence of two witnesses.

CLARENCE M. FAITHFULL.
